SIGNAL SWITCH

Frank J. Reddick, Newberry, S. C.

Application October 7, 1943, Serial No. 505,347

4 Claims. (Cl. 200—155)

My invention relates to electrically operated signaling devices for railroad crossings, and has among its objects and advantages the provision of an improved switch.

In the accompanying drawing:

Figure 1 is a plan view of the switch;

Figure 2 is a sectional view taken along the line 2—2 of Figure 1;

Figure 3 is a face view of a rotary switch element;

Figure 4 is a face view of a stationary terminal body which rotatably carries the switch element of Figure 3;

Figure 5 is a sectional view taken along the line 5—5 of Figure 4;

Figure 6 is a perspective view of a contact bar; and

Figure 7 is a diagrammatic view of an electric circuit illustrating two of the switches incorporated therein.

In the embodiment selected for illustration, the switch 10 of Figures 1 and 2 comprises a stationary body 12 of insulating material in which terminal screws 14, 16, 18 and 20 are anchored. A conductor bar 22 electrically connects the terminal screws 14 and 16. Extending upwardly from the upper face of the body 12 is an annular rib 24 having four high points 26 and four low points 28. The terminal screws 14, 16, 18 and 20 extend through the annular rib 24 and are spaced ninety degrees apart, with the heads 30 of the terminal screws respectively located at the low points 28.

The body 12 is provided with a central opening 32 for loosely receiving a long bolt 34 extending through an opening 36 in a switch element 38 comprising two arms 39 of insulating material and notched at 40 for interfitting engagement and arranged ninety degrees apart. A washer 42 is interposed between the head 44 of the bolt 34 and the switch element 38. Upon the bolt 34 is mounted a compression spring 46 engaging a washer 48 lying against the body 12 and a washer 50 supported by lock nuts 52 threadedly connected with the bolt. The bolt 34 is located at the axis of the annular rib 24.

The arms 39 lie in a common plane and each is provided with two V-shaped faces 54 arranged to ride on the annular rib 24. To one of the arms 39 is secured a conductor plate 56 having end formations 58 fitting the two V-shaped faces 54 on that arm. Pins 60 secure the plate 56 to its respective arm 39. The end formations 58 are arranged for engagement with the terminals 14

and 18 or 16 and 20, depending upon the position of the switch element 38.

In operation, two switches 10 are employed for a crossing. The terminals 14 and 16 of each switch 10 are electrically connected with an electrically operated signal 62, as by wires 64. The terminals 18 of the two switches are electrically connected by a wire 66, and a wire 68 electrically connects the two terminals 20. The wires 66 and 10 68 are electrically connected with a source of current 70, as by wires 72 and 74 which may be lugged to the wires 68 and 66, respectively.

The switch element 38 is rotated through movement of the engine in its passage across the signal switch. This is accomplished through the medium of levers on opposite sides of the engine and under the control of the engineer. Such devices are old and well-known in the art.

Because of the ascending and descending con-tour of the rib 24, a one-eighth turn of the switch element 38 causes the latter to make a quarter turn, since the spring 46 will cause the switch element 38 to continue rotation as the end forma-tions 58 pass over the high points.

In Figure 7, the signal circuit is open, with the two conductor plates 56 engaging the terminal screws 14 and 18 of their respective switches 10. As the switch element 38 of either switch is rotated to bring the conductor 56 of that switch into engagement with the terminal screws 16 and 20 of that switch, the circuit will be closed through the signal 62, and the signal circuit will be broken when the switch element 38 of the other switch 10 has been rotated to bring its conductor plate 56 out of engagement with the terminal screws 16 and 20.

Electrical devices other than the signal 62 may be connected with the terminals 18 and 20 without interfering with the signal circuit.

Without further elaboration, the foregoing will so fully illustrate my invention, that others may, by applying current knowledge, readily adapt the same for use under various conditions of service.

I claim:

1. In a switch of the type described, an insulative body having an annular flange provided with an undulating top surface having four high points and four low points respectively positioned between the high points, first, second, third and fourth terminals anchored to said body and ex-posed at the low points of said flange, said first and second terminals being electrically connected one with the other, said body being provided with an opening located at the axis of said flange, said high and low points being respectively spaced

forty-five degrees apart about the axis of said opening, a switch element comprising arms having V-shaped portions and crossing in right angular relationship and having a shaft extending through said opening, a conductor attached to one of the arms and having end formations fitting in the V-shaped portions and engageable with the first and third terminals in one position of the switch element and with the second and fourth terminals in another position of the switch element, and resilient means acting on said body and said shaft to yieldingly hold the switch element in engagement with said flange, with said high points so shaped and coacting with the V-shaped portions of the crossed arms as to cause the switch element to be cammed to a position rotated ninety degrees from its preceding position upon initial rotation of the switch element through at least forty-five degrees from its preceding position.

2. The invention described in claim 1 wherein said crossed arms are of insulating material and fitting one with the other to lie in a common plane, with each arm having edge formations engageable with said annular flange.

3. In a switch of the type designed for use with railway crossings having an electrically energized signal circuit adapted to be operated by a contact means on a vehicle passing over the crossing, comprising a fixed base element formed with an annular flange having an undulating upper face formed with two high points and two low points diametrically opposed to each other, con-

tact elements at the low points, a pivoted member having crossed arms carried on the base member and spring pressed to have pressing contact therewith, said arms having V-shaped portions diametrically opposed to each other and circumferentially aligned with the annular flange, a contact element carried by the pivoted element and having terminal formations fitting the V-shaped portions to provide a camming surface to move said pivoted element automatically to a position making or breaking the circuit when initially engaged and pushed by the means on the vehicle crossing the intersection.

4. In a switch of the type described for use with railway crossings having an electrically energized signal circuit, comprising a fixed base having a raised annular flange on its upper face and having an undulating upper face formed with two low points and two high points diametrically opposed to each other, contact elements at the low points, electric terminals connecting the opposed contact elements, a movable member above said base and having a pivot passing downwardly through the base between the contacts, a spring surrounding the pivot below the base and normally forcing the same downwardly, arms carried by said movable member and having V-shaped outer lower faces diametrically opposed to each other, and a V-shaped contact element connecting the ends of two opposed arms to automatically make or break the circuit when the arms are initially engaged and moved.

FRANK J. REDDICK.
